W. J. KOENIG,
EMERGENCY LAMP,
APPLICATION FILED DEC. 3, 1918.

1,344,206.

Patented June 22, 1920.

UNITED STATES PATENT OFFICE.

WILLIAM J. KOENIG, OF BROOKLYN, NEW YORK; ANNIE ALLEN ADMINISTRATRIX OF
SAID WILLIAM J. KOENIG, DECEASED.

EMERGENCY-LAMP.

1,344,206.

Specification of Letters Patent. Patented June 22, 1920.

Application filed December 3, 1918. Serial No. 265,126.

To all whom it may concern:

- Be it known that I, WILLIAM J. KOENIG, a citizen of the United States, and a resident of the city of New York, borough of Brooklyn, in the county of Kings and State of New York, have invented a new and Improved Emergency-Lamp, of which the following is a full, clear, and exact description.
- 10 This invention relates to portable or emergency lamps such as are commonly used in or about machine shops, engine rooms, automobiles, or the like, for the purpose of inspecting, repairing, or performing other duties in connection with such machines.
- 15 Among the objects of the invention is to provide an improved structure involving a lamp casing comprising not only a lamp socket and reflector, but also an electromagnet serving to hold the lamp automatically in any desired position as upon or against any convenient metallic support.
- 20 Another object of the invention is to provide a lamp structure of the character set forth in which the magnet winding is in a branch or auxiliary circuit including a normally open switch so that while the lamp will glow automatically as soon as the cord plug is attached, the magnet will not be
- 25 energized unless and until the lamp casing is put in supporting position against the aforesaid support at which time the magnet will be energized and automatically hold the lamp in position.
- 30 The details of construction upon which I rely to carry out the foregoing and other objects will be appreciated as this description progresses in connection with the accompanying drawings of which—
- 35 Figure 1 is a front elevation of my improved lamp in supported position, a portion of the base or magnet casing being broken away to show the automatic switch.
- 40 Fig. 2 is a vertical section approximately on the line 2—2 of Fig. 1.
- 45 Fig. 3 is a detail perspective view of the lamp socket.
- 50 Fig. 4 is a vertical sectional view of a modified form of lamp socket.
- 55 Fig. 5 is a detail plan view of a modified form of switch controlling the action of the electromagnet.
- 60 Fig. 6 is a vertical central section of the mechanism shown in Fig. 5.
- 65 Fig. 7 is a diagram of the electrical de-
- vices and indicating especially the relation of the lamp and electromagnet to the cord plug and battery; and
- 70 Fig. 8 is a detail view indicating the preferred manner of forming the shell joints.
- 75 Referring now more particularly to the drawings I show a lamp casing comprising a plurality of shell members 10, 11 and 12 pertaining respectively to the electromagnetic base, the socket and switch devices, and the lamp bulb hood or protecting reflector. The shell members 10 and 11 are made preferably as hollow sheet metal cylinders which may be connected together separably by any suitable means such as screw threads or by means of screws 13 passing therethrough. As shown best in Fig. 1 these cylindrical shells may be made with meeting edges abutting directly against each other along a line 14 and locked in such position by means of a plurality of dumb-bell keys 15. This type of connection is exceedingly important in the formation of shells of relatively thin or light material by forming the keys 15 of a slightly thicker material and cut to exactly fit similarly shaped notches 15' in the shell, the keys being put in place and slightly swaged or upset, producing an exceedingly strong and reliable joint.
- 80 Within the base shell 10 is fixed in any suitable manner an electromagnet 16 having a core 16^a and a winding 16^b. A base disk 17 of insulation surrounds the lower end of the core just within the lower end of the shell 10. At the upper end of the core is another disk 18 of fiber or the like below which is arranged a metallic disk 19 through which the terminals 20 and 21 of the winding 16^b pass by means of registering holes formed through these disks.
- 85 As above intimated the shell 11 is designed as a holder or protector for the metallic lamp socket 22 and wiring switches and connections both for the lamp base 23 and the electromagnet. The socket 22 is provided with any usual or well known means such as bayonet slots for attachment of the lamp base 23, and within the socket is arranged a contact piece comprising a 90 slideable disk 24 having either one contact pin 25 as shown in Fig. 2 or two contact pins 25' for a double contact lamp base as shown in Fig. 4.
- 95 A suitable source of energy is indicated 110

at 26 and with which the cord plug 27 of well known construction is adapted to co-operate for the purpose of carrying a current through conductors 28 and 29. The conductor 28 is attached to the metallic socket 22 at 30, while the other conductor leads to the lamp and is also connected with the winding terminal 20. The wire 29 is associated with the contact pin 25 whereby when the socket 27 is attached to the battery the lamp is lighted automatically the current passing through wire 28 through the shell 22, lamp base 23, contact pin 25, through intermediate connections with the wire 29. These intermediate connections in Fig. 2 are shown as comprising insulated wires 31 and 32 twisted or otherwise fastened upon a pair of horns 33 formed as integral parts of a fiber collar 34 carried by the socket 22. These horns afford a convenient means for making the wire connections. The disk 24 is resiliently supported through a spring 35 upon a fixed disk 36 locked in any suitable manner within the lower portion of the socket 22. The disk 36 is provided with a central hole through which one end of the pin is guided for movement under the force of the lamp base 23 when put into locking position.

It will thus be seen that while the lamp will always glow when the plug 27 is connected to a source of energy the circuit through the magnet 16 is not normally completed. To complete this circuit therefore and energize the magnet, I show in Fig. 2 an automatic switch in the form of a plunger pin 37 slidable in or through a central bore in the core 16 and having a head at its upper or inner end against which a contact spring 38 constantly bears through a sleeve of insulation 39. This spring 38 is so fixed to the disk 18 as to force the pin 37 normally downward to project the opposite end thereof below the plane of the base end of the base 10. The terminal 21 of the magnet winding is connected to the spring contact 38. The free end of the contact 38 lies opposite some portion of the metallic socket 22, hence when the free end of the pin 37 is brought into direct contact with any support to which the lamp is intended to be fixed the pin will be moved immediately to cause the contact 38 to engage the socket 22 and thereby close the circuit through the magnet automatically. This will be understood by comparing Figs. 1 and 2. It will thus be seen that no attention or effort is required on the part of the operator to energize the magnet, he simply manipulates the lamp casing to place it where he wants it and when so placed the automatic switch pin 37 will cause the closing of the circuit and thereby the lamp will be held in the place desired until he removes it later by simply withdrawing it from its support. When so withdrawn the spring 38 automatically leaves the point of contact with the socket 22 throwing thereby the pin 37 down for a subsequent contact. The action of the magnet is independent of that of the lamp and so while the lamp is constantly burning when the plug 27 is in place the magnet is not energized except when the operator desires to support the lamp on or against any metallic circuit in convenient reach. It will be understood that the power of the magnet is sufficient to hold the lamp in any position irrespective of gravity, but such power will not prevent the operator from withdrawing the lamp from its support when the operation is finished.

The socket 22 is provided with a pair of spaced parallel prongs 40 which straddle the switch spring 38 and which are adapted to interlock in any suitable manner in or through the fiber disk 18 whereby the socket 22 is held in proper position within the casting 11 and with respect to the electromagnet.

The hood 12 is preferably made of two parts 12^a and 12^b fastened together at a median transverse joint 12^c. The lower portion 12^a is provided with a neck member 12^d constituting a means of connection with the upper end of the shell 11 and also an internal bottom reflector insulated, however, from the socket 22 by means of a sleeve 41 of fiber or the like. This form of hood constitutes not only the best possible form of protector for the lamp bulb, but also acts as a reflector serving to throw the light strongly out through a side window 42.

In Figs. 5 and 6 I show a modified form of electromagnet switch comprising a fiber arm 43 pivoted by means of a screw 44, or its equivalent, fitted into the upper end of the core bore 45. The provision of the bore for the accommodation of the pin 37 in the manufacture of these devices enables either the manufacturer or any other person to employ either type of switch with a minimum amount of trouble or expense. The arm 43 carries a spring contact 38 adapted to co-operate with a fixed contact 46 associated with one of the winding terminals. This arm 43 obviously will project internally through the shell 11 and so be in position to be operated by the operator's fingers in order to energize the magnet.

I claim:

1. In an emergency lamp, the combination of an electromagnet, a disk of insulating material at one end of the magnet through which the terminals of the magnet windings pass, a movable contact member in connection with one of said terminals; a lamp socket having a pair of supporting members straddling said switch and fixed to said disk, circuit wires leading to the magnet, and means projecting through to

120

the outside of the lamp casing to actuate said movable switch.

2. In an emergency lamp, the combination of a casing, an electromagnet within the casing including a core having a longitudinal bore, a lamp socket, means to rigidly support the lamp socket with respect to the

magnet, said supporting means comprising a pair of spaced prongs, a movable switch between said prongs and adapted to engage 10 the socket, circuit wires leading to the magnet and socket, and means movable through the core bore to actuate said movable switch.

WM. J. KOENIG.
